UNITED STATES PATENT OFFICE.

G. L. INGERSOLL, OF CLEVELAND, OHIO.

WATER-HEATER FOR STOVES.

Specification forming part of Letters Patent No. **71,490**, dated November 26, 1867.

To all whom it may concern:

Be it known that I, G. L. INGERSOLL, of Cleveland, in the county of Cuyahoga and State of Ohio, have invented certain new and useful Improvements in Heaters; and I do hereby declare that the following is a full and complete description of the same, reference being had to the accompanying drawings, making a part of this specification, in which—

Figure 1 is a side view of the heater and stove. Fig. 2 is a front view. Fig. 3 is a vertical section.

Like letters of reference refer to like parts in the views.

In Fig. 1, A represents an ordinary cook-stove, at the back end of which and connected to the pipe B is an extension-plate or bottom, C, supported by legs D. On this plate is erected the heater E, of which it forms the bottom. This heater consists of an oval or oblong case, F, inclosing a pair of cylindrical boilers, G, Fig. 3, connected to each other by the pipes or tubes H, thereby establishing a direct and free communication between them.

At the top of each boiler is a tube or pipe, I I', one of which (the induction-pipe I') extends to near the bottom of the boiler, as indicated by the dotted lines, Fig. 3. These pipes are for the purpose of filling the boilers and for drawing off the water when heated.

The practical use and management of this heater is as follows: The boilers being filled, which, it will be observed, is done from the top, the water is heated by the waste heat and smoke of the stove as it passes out through the pipe B into the case F, and ascends therein between and around the boilers to the top of the case, from which it escapes into the chimney through the pipe J. It will be obvious that by this arrangement of the heater the waste heat only is used in heating the water, whereas in the ordinary way of heating water for bathing purposes the heat is taken directly from the fire-box by the introduction of pipes within the box, and thence leading to a reser-

voir or boiler located at some distance from the stove, involving by this means a large expense in the use of fuel. By this means the water is soon raised to a high degree of heat, and which is conveyed by a pipe attached to the education-pipe I to the upper rooms. The supply-pipe being connected to the pipe I', and carried to the same height as the education-pipe, or connected to the hydrant, the boilers being so constructed as to sustain the pressure, the pressure of said hydrant will force the heated water to the rooms above, and is there drawn off as it may be needed.

By supplying the boilers with water from the top and conducting it to the bottom of the boiler through the pipe I', it will be obvious that the cold water will become heated in a much shorter time than if introduced at the top; hence a saving of fuel is obtained without any inconvenience or increase of expense.

This heater can be applied to any of the ordinary cook-stoves or ranges, as it is made entirely separate from the stove, and mounted upon a separate bottom back and away from the top of the stove; hence it is not in the way of a free access and use of all the holes in the top, and offers no obstruction to the draft.

On applying the heater to the extension-stove the bottom C will not be required, as it is simply placed on the top of the stove in the position usually occupied by the ordinary water-boiler.

What I claim as my improvement, and desire to secure by Letters Patent, is—

A cylindrical boiler or boilers, A, connected to each other by pipes H, and provided with induction and education pipes I I', when inclosed within a case, F, with or without the extension-bottom C, in combination with the stove A, for the purpose and in the manner substantially as set forth.

G. L. INGERSOLL.
